(57) **CLAIM**

The ornamental design for an oval lighted address plaque, as
shown and described.

DESCRIPTION

FIG. 1 is a perspective view of the oval lighted address
plaque;

FIG. 2 is a frontal plan view of the oval lighted address
plaque;

FIG. 3 is a rearward plan view of the oval lighted address
plaque;

FIG. 4 is a top side elevational view of the oval lighted
address plaque;

FIG. 5 is a bottom side elevational view oval lighted address
plaque;

FIG. 6 is a right side elevational view of the oval lighted
address plaque; and,

FIG. 7 is a left side elevational view oval lighted address
plaque.

The broken line showing of address numbers is for illustrative
purposes only and forms no part of the claimed design.
